No 835

Patented October 1st 1856

Pls 835

Daniel Wilson, of Nashua, N.H.
Letters Patent No. 835. Dated October 7, 1856.

The schedule referred to in these Letters Patent and making part of the same.

To all whom it may concern:

Be it known that I, Daniel Wilson, of Nashua, in the County of Hillsborough, and State of New Hampshire, have invented or produced a new and original design for a bookshop, and I do hereby declare that the following is a full, clear and exact description of the same.

The accompanying drawing shows a front, top, and end elevation in perspective.

Dec. 835

of the stone, with the various ornaments and mouldings formed thereon, which constitute my design. A proper pattern should be formed for each of the parts constituting the front and both ends of the stone, and the ornaments thereon, as seen in the drawing.

The front plate, immediately before the fire and grate, is made so that it can be conveniently removed when desired. The carving of these parts, which constitute the front and both ends, is made in bas relief as indicated in the annexed drawing.

The top of the stone can be formed, as seen in the drawing, with any desired number of covers thereon, and properly fitted to the stone.

The back of the stone can be formed any convenient shape, to fasten to each of the ends of the stone, as may be desired.

Having thus described the nature of my design or production:

I claim the design, configuration, and arrangement in bas relief on the ends and front of the stone, as described and shown, forming a new and original design for a cooking stove.

Witnesses.
